UNITED STATES PATENT OFFICE.

ALFRED INGRAM AND HARRY INGRAM, OF BROOKLYN, NEW YORK, ASSIGNEES, BY MESNE ASSIGNMENTS, TO HAZEL-ATLAS GLASS COMPANY, OF WHEELING, WEST VIRGINIA, A CORPORATION OF WEST VIRGINIA.

CLOSURE FOR JARS, TUMBLERS, AND OTHER RECEPTACLES.

Application filed June 23, 1920. Serial No. 391,054.

This invention relates to improvements in closures for jars, tumblers and other receptacles of the character comprising applied caps and gaskets.

Our invention involves a new construction of cap, and in the construction of our cap we have obtained several important advantages one being that the cap may be securely held in sealing position on the jar or tumbler either by atmospheric pressure, that is, by what is commonly known as the vacuum sealing process, or merely by the gripping action of the gasket when it is in position surrounding the upper side wall of the jar or tumbler or with the aid of the mechanical features of the cap and particularly those features thereof which may be spun under a shoulder on the jar or tumbler and cooperate with other features in effecting an entirely reliable sealing action and which, without the use of the vacuum, will permit the sterilizing of the contents of the package to a high degree, say, 240 degrees Fahrenheit, without danger of the cap being blown off from the receptacle and without the aid of any external pressure. A further purpose of the invention is to provide means whereby a very tightly fitting cap may be conveniently detached from its jar or tumbler with the use of an ice-pick or other pointed instrument which may be ordinarily found in households, and in this respect our invention seeks to remedy the well recognized difficulties incident to the removing of caps, possessing proper sealing qualities, from jars or tumbles containing food products. In accordance with our invention we provide the cap with a depending skirt portion having a depending tear-off tab of special construction permitting the use of an ice-pick or other convenient instrument for tearing, with a lever action, the tab upwardly from its normal position and through the skirt of the cap to a sufficient extent to so release the cap that the cap may be readily removed from the jar, one of the important advantages of our special construction of tear-off tab being not only that it may be torn upwardly with the use of a pointed instrument, but that instead of being ripped through on the operation of the instrument against the same, it will resist being torn itself and permit the instrument to tear the tab upwardly

through the skirt on the cap to a position 55 at which the cap is left in condition for convenient removal.

Our invention may be applied to jars and tumblers of various shapes and constructions and is capable of embodiment, with advantage, in closure caps of various kinds.

The invention will be fully understood from the detailed description hereinafter presented, reference being had to the accompanying drawings, in which:

Fig. 1 is a side elevation of the closure of our invention applied to a jar, the jar being shown as partly broken away;

Fig. 2 is a bottom view of the cap, the jar being omitted;

Fig. 3 is a vertical section through a portion of the jar and closure, taken on the dotted line 3-3 of Fig. 1, and illustrating the manner of applying a tool to the tear-off tab of the closure for aiding in the removal 75 of the closure from the jar;

Fig. 4 is a corresponding view showing the tear-off tab as having been torn upwardly from the closure to the top thereof;

Fig. 5 is a side elevation, partly broken 80 away, of the jar and closure, taken from the left hand side of Fig. 4, and Fig. 5 indicates by the dotted line 4-4 the section on which Fig. 4 is taken;

Fig. 6 is a side elevation, partly broken 85 away, of a modified form of closure of our invention applied to a jar or tumbler differing in outline from the jar shown in Fig. 1, the jar shown in Fig. 6 being partly broken away;

Fig. 7 is a side elevation on a larger scale, partly broken away and partly in section, of the jar and closure shown in Fig. 6 on a smaller scale, Fig. 7 being a side elevation which may be regarded as having been taken 95 from either the right hand side or left hand side of Fig. 6;

Fig. 8 is a side elevation, partly broken away and partly in section, of a jar or tumbler having a modified form of cap 100 closure with our invention applied thereon, and Fig. 8 illustrates the manner of employing an ice pick or like instrument for lifting upwardly the tear-off tab with which the closure is equipped, and

Fig. 9 is a sectional view through a further modified form of jar and cap-closure embodying our invention.

In the drawings, referring to Figs. 1 to 5 inclusive, 10 designates a jar of known type having a laterally projecting downwardly diverging side-rim portion 11 affording at 5 its lower edge a horizontal shoulder 12, and 13 indicates the cap of our invention, said cap comprising a top 14 and downwardly depending skirt or flange portion 15 which is annularly recessed in its upper portion, 10 at 16, to receive a gasket 17 which, in the sealing position of the closure, tightly engages the exterior of the rim 11 and the inner wall of the recessed portion of the skirt or flange 15, as shown in Fig. 3. The 15 skirt or flange 15 of the cap has, at the lower edge of the recess 16, an annular shoulder 18 which affords a seat for the lower edge of the gasket 17 and cooperates with the general features of the cap in closely binding the gasket against the side wall of the receptacle and in securing an effectual seal. 20

The cap 13 extends downwardly over the side of the receptacle 10 to about the horizontal plane of the shoulder 12, and at the 25 lower edge of its skirt portion or flange 15 said cap is formed integrally with one or more depending tear-off tabs 19, the cap shown being, in the present instance, equipped with four of said tear-off tabs 19 arranged 30 equidistant from one another, as shown in Fig. 2. The tear-off tabs 19 are preferably of substantial width at their upper edges and thereat are spun under the shoulder 12 whereby the metal of the cap, 35 at the upper edges of the tabs 19, is given an arc formation 20 which projects inwardly below the shoulder 12 and cooperates with the shoulder in resisting upward movement of the cap at all times and especially during 40 the sterilization of the contents of the jar at a high temperature. The arc formations or shoulders 20 formed at the upper ends of the tabs 19 by the spinning or bending of the tabs beneath the shoulder 12 also 45 increases the strength of the cap and permits us to employ metal of reasonable thinness and tenderness in the construction of the cap, it being desirable that metal of this character be employed on account of lightness of weight and, among other advantages, 50 because it enables the tearing upwardly of the tabs 19 without undue exertion. We shall, however, whenever the occasion so requires, employ good stiff metal in the 55 caps 13, and hence we also make provision in connection with the tabs 19 for the tearing upwardly of the same to release the cap even though the metal of the cap might ordinarily be of a character to resist the 60 tearing upwardly of the tabs with the use of the fingers. The tabs 19 are distinctive in two particulars, one being that each tab is formed with an opening or hole 21 extending through it at a convenient point 65 above its lower edge and below the arc- shoulder 20 created, in Fig. 1, at the upper edge of the tab, and this hole 21 is adapted to receive a pointed instrument, as an ice-pick 22 (Fig. 3), to be used as a lever for prying the tab upwardly and tearing the 70 same upwardly through the skirt of the cap or to a position substantially as indicated in Figs. 4 and 5. It has heretofore been proposed to employ tear-off tabs on closures, but these tear-off tabs have been inefficient 75 when on closures formed of stout metal, because of their resistance to the action of the fingers in the effort of tearing off the tab. In accordance with our invention we provide the tabs 19 with the holes 21 so that 80 the pointed instrument may be conveniently applied to the tabs and used as a lever for tearing the tabs upwardly, as will readily be seen on reference to Fig. 3. The instrument may be applied downwardly through 85 the hole 21, as we show in Fig. 3, or upwardly through said hole, as may be preferred. A further important feature of the tear-off tab 19 resides in the fact that the tear-off tab is reinforced to prevent the instrument 90 22 from tearing through the tab itself instead of tearing the tab upwardly through the skirt or flange 15 of the cap, and we regard this reinforcing of the tab for the purpose mentioned as very important, since 95 it is well known that many caps fit tumblers and jars so tightly that they can only with great difficulty be removed therefrom. In the present instance we form the reinforcement for the tabs 19 by curling over 100 the lower edge of the metal of the tab, as at 23, so as to provide the reinforcement at the lower edge of the hole 21, such reinforcement in that position serving to effectually resist the action of the tool 22 against the 105 tab and which action, in the absence of the reinforcement, would, in the case of thin or tender metal, rip through the tab instead of tearing the tab upwardly through the skirt or flange 15. We do not limit our invention to the curling over of the lower edge of the tab, as at 23, to provide the reinforcement, since the lower edge of the tab might be turned over flatwise or otherwise shaped to reinforce the tab. The reinforcement is 110 for the benefit of the tab as a whole and particularly to prevent the hole 21 from being torn through under the action of the tool 22, and hence one of the main purposes of the reinforcement is to maintain the 115 integrity of the hole 21. We therefore do not limit the invention to the special detail shown for reinforcing the hole 21 or maintaining the integrity of the same, since it is new with us both to provide the tab with 120 the hole 21 and with a reinforcement enabling the use of the tool 22 for so releasing the cap that it may be conveniently removed.

The cap 13 tightly fits upon the jar 10 and 130

the gasket on the placing of the cap upon the jar, becomes deformed into the recess 16 and engages the cap and jar with sealing effect, and when the tabs 19 are employed and at their upper ends spun under the shoulder 12, the contents of the jar may be subjected to high heat for sterilization purposes without danger of the cap blowing off even though the surfaces around the mouth of the jar 10 may be slightly diverging or inclined, as shown in Figs. 2 and 4. When a tab 19 is torn upwardly through the skirt or flange 15 of the cap, the gasket 17 becomes exposed, as shown in Figs. 4 and 5, and the holding 15 quality of the cap released to a sufficient extent to permit of the convenient removal of the cap.

In Figs. 6 and 7 we illustrate our invention as applied to a tumbler or jar 24 having plain side walls about its rim, and in Figs. 6 and 7 the cap shown is identical with the cap illustrated in Fig. 1, with the exception that since the tumbler or jar 24 does not possess the shoulder 12 of the jar 25 10, the upper ends of the tear-off tabs extend downwardly close against the sides of the tumbler or jar 24. In Figs. 6 and 7 we number the cap as a whole 25, the flange or skirt portion thereof 26 and the tear-off tabs 30 27, these tabs each having a hole 28 and a reinforcement 29 corresponding with the hole 21 and reinforcement 23 of Fig. 1. The cap 25 contains in the upper portion of its skirt or flange a recess 29 holding the gasket 35 30, and at the lower edge of the recess 29 is formed an inwardly and downwardly converging shoulder 31 corresponding with the shoulder 18 of Fig. 3. The construction shown in Figs. 6 and 7 is so nearly identical 40 with the construction shown in Figs. 1 to 5 inclusive that further detailed description with respect to Figs. 6 and 7 is not required. We may say, however, that the closures shown in Figs. 6 and 7 will be secured by the 45 vacuum process, as indicated in Fig. 7, and that two tear-off tabs 27 will be ample for the cap 25. In fact one tear-off tab 27 may be alone made use of on any of the caps presented herein, and therefore we do not limit 50 our invention to the employment of four tabs or two tabs or any plural number of tabs.

In Fig. 8 we illustrate our invention as applied to a known type of tumbler or jar 30 and to a cap 31 in whose skirt portion is confined a gasket 32 which by vertical pressure applied to the beading of the said skirt portion is tightly squeezed against the side walls of the tumbler or jar 30. The special 55 construction of cap shown in Fig. 8 is one which has been found to be very difficult indeed to remove from jars or tumblers, and hence we show one form of our invention in connection with the cap 31, which we equip 60 with the integral tear-off tabs 33 possessing

the hole 34 and reinforcement 35, the hole 34 being intended to receive an ice-pick or other pointed tool 36 to be used as a lever in tearing upwardly the tab through the beaded portion of the skirt of the cap so as to fully expose the gasket 32 and permit the tearing away, when necessary, of the same.

In Fig. 9 we illustrate our invention as applied to a preferred form of cap 37 and tumbler or jar 38. In the construction shown in Fig. 9 the upper exterior rim portion of the jar or tumbler is formed with a recess 39 at whose lower edge is a shoulder 40 which supports a gasket 41 confined within the upper outer edges of the skirt portion 42 of the cap 37. Below the annular recess 39 the outer sides of the jar converge inwardly and downwardly on a graceful curvature and thereby an annular shoulder 43 is formed on the jar below which shoulder the lower edge portion of the skirt or flange 42 is spun, as at 44. The flange or skirt 42 is formed integrally with depending tear-off tabs 45 having holes 46 and reinforcements 47, said holes 46 and reinforcements 47 corresponding with the holes 21 and reinforcements 23 of Fig. 1 and being provided for a like purpose.

Our invention may thus be embodied in several forms of caps and utilized in connection with several forms of jars and the like.

What we claim as our invention and desire to secure by Letters-Patent, is—

1. In combination with a receptacle, a closure therefor comprising a cap of thin, flexible and comparatively tender material having a depending skirt portion containing an annular recess which extends around the receptacle, a gasket in said recess to form an annular side seal and a tear-off tab integral with and extending from the lower edge of said skirt portion, said tab containing a hole to receive a pointed instrument with which the tab may be torn upwardly through said skirt portion to release the cap.

2. In combination with a receptacle, a closure therefor comprising a cap of thin, flexible and comparatively tender material having a depending skirt portion containing an annular recess which extends around the receptacle, a gasket in said recess to form an annular side seal and a tear-off tab integral with and extending from the lower edge of said skirt portion, said tab containing a hole to receive a pointed instrument with which the tab may be torn upwardly through said skirt portion to release the cap, and said tab having a reinforcement to prevent the instrument from ripping through the end of the tab.

3. In combination with a receptacle, a closure therefor comprising a cap of thin, flex-

- ible and comparatively tender material having a depending skirt portion containing an annular recess which extends around the receptacle, a gasket in said recess to form an annular side seal and a tear-off tab integral with and extending from the lower edge of said skirt portion, said tab containing a hole to receive a pointed instrument with which the tab may be torn upwardly through said skirt portion to release the cap, and said tab being folded upon itself below said hole to provide a reinforcement to prevent the instrument from ripping through the tab.
15. 4. In combination with a receptacle, a closure therefor comprising a cap of thin, flexible and comparatively tender material having a depending skirt portion containing an annular recess which extends around the receptacle, a gasket in said recess to form an annular side seal and a tear-off tab integral with and extending from the lower edge of said skirt portion and having a reinforced hole to receive a pointed instrument with which the tab may be torn upwardly through said skirt portion to release the cap.
20. 5. In combination with a receptacle, a closure therefor comprising a cap of thin, flex-

ible and comparatively tender material having a depending skirt portion containing an annular recess which extends around the receptacle, a gasket in said recess to form an annular side seal and tear-off tabs integral with and extending from the lower edge of said skirt portion at opposite sides of the cap and containing holes to receive a pointed instrument with which the tabs may be torn upwardly through said skirt portion to release the cap.

30. 6. In combination with a receptacle, a closure therefor comprising a cap having a depending skirt portion containing an annular recess which extends around the receptacle, a gasket tightly filling said recess and engaging the side of the receptacle to form an annular side seal and a tear-off tab integral with and extending from the lower edge of said skirt portion and containing a hole to receive a pointed instrument with which the tab may be torn upwardly through said skirt portion to release the cap, said hole being reinforced to prevent the instrument from ripping through the tab.

40. ALFRED INGRAM.
